UNITED STATES PATENT OFFICE.

WILLIAM A. SEXTON, OF ST. LOUIS, MISSOURI.

SODA-FOUNTAIN.

No. 887,969. Specification of Letters Patent. Patented May 19, 1908.

Application filed April 29, 1907. Serial No. 370,872.

To all whom it may concern:

Be it known that I, WILLIAM A. SEXTON, a citizen of the United States, residing at the city of St. Louis, State of Missouri, have invented a certain new and useful Improvement in Soda-Fountains, of which the following is a specification, reference being had to the accompanying drawings, forming part of this specification, in which—

Figure 1 is a perspective view of my new soda fountain; Fig. 2 is a detail sectional view of the cans and coils, on the line 2—2, Fig. 1, the cabinet or casing not being shown; Fig. 3 is a top plan view of the cans and coils, the cabinet or casing not being shown; and Fig. 4 is a sectional view on the line 4—4, Fig. 1.

This invention relates to a new and useful improvement in soda fountains, the object being broadly to provide a combined ice-cream cabinet and soda fountain, wherein the soda-water is cooled by the ice used to preserve the ice-cream.

With this object in view, my invention consists in the novel construction, arrangement, and combination of the several parts, all as will hereinafter be described and afterwards pointed out in the claims.

Referring to the drawings, wherein like letters of reference refer to like parts throughout the several views, 1 indicates a cabinet provided with compartments 2, 3, and 4, and with the air-space 5 around its sides and preferably lined with tar-paper or tin, making the cabinet a good refrigerator.

E and F indicate large metal cans arranged in the compartments 2 and 4, respectively, said cans resting on raised platforms 2' and 4' in said compartments 2 and 4, respectively, whereby an air-space is left therebeneath. The said cans E and F are received and held in position by the ribs or flanges P and O on said platforms 2' and 4', respectively. The cans E and F occupy the greater part of the space in said compartments 2 and 4 and extend close up to the top thereof, C and D indicating separate cylindrical portions of metal fitting around the tops of said cans E and F and extending up to the top of the cabinet 1, so as to prevent the ice hereinafter mentioned getting into said compartments 2 and 4. A and B indicate covers for said cans and for the openings in the top of the cabinet 1 over said compartments 2 and 4.

E' and F' indicate, see Fig. 2, what may be called ice-cream cans adapted to receive and

hold the ice-cream, the cans E' and F' being smaller than, and received in, said cans E and F and resting on the raised platforms e and f in the bottoms of said cans E and F, respectively, said platforms e and f being provided with drain openings e' and f', respectively, as shown. Around the outside of said cans E' and F' and within the cans E and F the ice is designed to be placed or packed for not only preserving the ice-cream in said cans E' and F', but also for cooling the soda-water, as hereinafter described. The ice, being packed directly or immediately against the inner can or ice cream receptacle, will also, should the ice cream in said can or receptacle become soft or melted from any cause, again freeze the ice cream, which would not occur if the ice were not packed directly against the ice-cream can.

I indicates a pipe leading from some source of soda-water supply not shown and entering the can F near its bottom beneath the platform f, where it is formed into the coil L', said pipe or metal tubing then passing through an opening in said can F to the outside thereof, where it is coiled several times around said can F, as indicated by the letter L. The outer end of the pipe of coil L might now be connected with the soda-draft Y, but I prefer, for more extended cooling purposes, to connect the outer end of pipe of coil L by means of the connecting-pipe M with the coils N' and N in and around can E, the coils N' and N being of the same construction and communicating together in like manner as the coils L' and L, the outer end of the pipe or tubing of coil N extending up to the top of the cabinet 1 where connection is made through the coupling T with the soda-draft Y. This practically continuous coil of tubing just described is what I term the soda-water coil, the soda-water therein being cooled by the ice within the cans E and F, as is obvious, the necessary power for forcing the soda-water through said coil or coils being supplied by the soda-carbonators.

J indicates a pipe leading to some suitable source of drinking-water supply, the pipe J being coiled around said can F, as at K, and then extending to the top of the cabinet 1 where connection is made through the coupling U with the cold-water draft Z, the water in the pipe J and coil K being also cooled by the ice in the can F.

Q and R indicate drain pipes leading from the bottoms of said cans E and F through

compartments 2 and 4, respectively, into pan S in compartment 3, from which the water is drained to the exterior through the drain pipe V, the compartment 3 serving also as a 5 cooling chamber for bottles of other liquids, etc.

By the construction above described, it is seen that one supply of ice surrounding the ice-cream cans not only serves to preserve the ice-cream therein, but also serves to cool the soda-water and plain water used at the fountain, thus materially reducing the expense of supplying ice. It will also be seen that one cabinet serves both for an ice-cream chest and a soda fountain, including water-coolers, thus not only taking up less room in a store, but doing away with the expense of 10 separate ice-cream chest, soda-fountain, water-cooler, and ice-box for other goods, and at the same time, the water, passing 15 through a coil and not coming into contact with the ice, will not take up foreign particles from the ice or have the taste of ammonia. It will further be seen that the cabinet 20 and cooling apparatus is easily assembled and repaired, should any repairs become necessary. It is also obvious that while I have shown and described a cabinet having 25 but three compartments and two cans with the cooling coils there-around, either more or less compartments and cans and cooling coils could be used without departing from the 30 nature and spirit of my invention.

Having thus described my invention, what

I claim and desire to secure by Letters Patent is:

1. In a soda fountain, the combination with a can adapted to receive a receptacle for ice-cream and ice therearound, of a coil of metal tubing arranged in the bottom of said can, a platform provided with drain openings within said can over said coil, a drain pipe leading from said can to the exterior, a second coil of metal tubing around the outside of said can and communicating with said first-mentioned coil, and a draft connected to said metal tubing; substantially as described. 45

2. In a soda fountain, a metal can, a coil of metal tubing arranged inside said can and leading to a source of soda-water supply, a 50 platform provided with drain openings within said can and over said coil, a second coil of metal tubing around the outside of said can and communicating with said first-named coil, a soda-draft connected to said second-named coil, and a receptacle adapted to receive ice-cream arranged in said first-named can, a space being left around said receptacle for receiving ice or other cooling material; substantially as described. 55

In testimony whereof, I have signed my name to this specification in the presence of two subscribing witnesses.

WILLIAM A. SEXTON.
